UNITED STATES PATENT OFFICE.

HARVEY CLINTON REED, OF HOLMESBURG, PENNSYLVANIA.

DESIGN FOR A PUZZLE-BOX.

SPECIFICATION forming part of Design No. 26,911, dated April 13, 1897.

Application filed February 26, 1897. Serial No. 625,217. Term of patent 7 years.

To all whom it may concern:

Be it known that I, HARVEY CLINTON REED, a citizen of the United States, residing at Holmesburg, in the county of Philadelphia and State of Pennsylvania, have invented and produced a new and original Design for Puzzle Boxes or Cases, of which the following is a specification, reference being had to the accompanying drawings, which form a part thereof.

In the drawings forming part of this specification, Figure 1 is a plan view of my improved puzzle box or case; and Fig. 2, a transverse section thereof on the line 2 2, these two views being deemed necessary to fully illustrate my design.

The leading feature of my design consists of a circular box or casing composed of a bottom 5, a circular vertical wall or flange 6, within which and centrally thereof is a circular chamber 7, which is closed at the top, as shown at 8, and the side walls of which are provided at the opposite sides thereof with openings 9, four of said openings being provided, and between the openings 9, on the inner side of the circular side walls of the chamber 7, are curved or segmental plates 10, which are shown in dotted lines in Fig. 1, and two of which are shown in full lines in Fig. 2, and centrally of the circular chamber 7 is a circular vertical wall or flange 11, whereby a small central circular chamber is formed,

in one side of which is an opening, as shown in dotted lines in Fig. 1.

Arranged between the circular vertical wall or flange 6 of the box or casing and the central circular chamber 7 are two concentric circular vertical walls 12 and 13, whereby concentric circular chambers 14, 15, and 16 are formed, and formed in the concentric circular vertical walls 12 and 13 at regular intervals are openings or passages 17.

The upper surface of the bottom 5 is smooth and regular throughout, and the entire plan and form of the box or casing are symmetrical and regular, the walls or flanges 6, 12, and 13 being all circular in form and vertical, and the central chamber 7 being also circular in form, and the circular spaces or chambers 14, 15, and 16 being all of equal width in cross-section.

Having fully described my invention, I claim as new and desire to secure by Letters Patent—

The puzzle box or case herein shown and described.

In testimony that I claim the foregoing as my invention I have signed my name, in presence of the subscribing witnesses, this 22d day of February, A. D. 1897.

HARVEY CLINTON REED.
